(57) **CLAIM**

The ornamental design for a noise abatement microphone attachment, as shown and described.

DESCRIPTION

FIG. 1 is a left side view of a noise abatement microphone attachment showing my new design;
FIG. 2 is a top plan view thereof;
FIG. 3 is a right side view thereof;
FIG. 4 is a bottom plan view thereof;
FIG. 5 is a front view thereof;
FIG. 6 is a perspective view thereof; and,
FIG. 7 is a back view thereof.

The broken lines shown in the drawing depict portions of the noise abatement microphone attachment that form no part of the claimed design.
